SEPARATION OF SOLID PARTICLES FROM FLUIDS

Horace Freeman, Three Rivers, Quebec, Canada,
assignor to Nichols Engineering & Research
Corporation, New York, N. Y., a corporation of
Delaware

Continuation of applications Serial No. 68,667,
March 13, 1936, and Serial No. 111,578, November
19, 1936. This application August 24, 1937,
Serial No. 160,578. In Canada March 11, 1936

18 Claims. (Cl. 92—28)

This invention relates to the separation of solid or heavier particles, such for example as impurities from liquids, the classifying of fluid suspensions, and apparatus for such purposes.

5 This application comprises a continuation of my applications Ser. No. 68,667, filed March 13, 1936, and Ser. No. 111,578, filed November 19, 1936.

Among other uses, for the separation of fluid suspensions, the invention is particularly adapted

10 for the separation of impurities from suspensions of paper-making stock or other fibers in water. Such impurities usually include particles very close in specific gravity to both the fiber and the water itself, and hence the problem of thoroughly 15 removing such particles to the extent necessary for making satisfactory paper, is generally difficult and expensive. For example, such impurities may include ground particles of the knotty portions of wood and the like. Other impurities 20 generally only slightly less difficult to adequately remove, comprise fine grit as from the pulp grinders, sand, silt, scale, sawdust, and compacted lumps of pulp, pitch or rosin.

Some paper pulp suspensions may also embody 25 China clay, the removal of which with the impurities is to be avoided. The present invention is particularly adapted for the removal of impurities from suspensions of China clay, and also from such suspensions with pulp, without danger of 30 removing the desired fine China clay, while at the same time any oversize particles of the clay, which would be as troublesome as impurities, are readily removed. The invention is also well adapted for the refining or classifying of a large 35 variety of materials similar to China clay suspensions.

Heretofore in preparing pulp for paper manufacture, the removal of impurities and oversize particles such as above referred to, has generally 40 involved more or less elaborate apparatus, expensive and sometimes troublesome to maintain and operate. Yet if particles of sand or the like are not quite thoroughly removed from the paper-making stock, substantial percentages of the paper product will be marred by imperfections and has to be discarded. Also the rollers of the paper-making machines as well as the lithographing and printing plates, etc., will be scarred or subjected to excessive wear. One of the objects of the present invention is to eliminate substantially all of 45 these troublesome impurities from paper-making stock with a method and apparatus which is uniformly dependable, and inexpensive in operation.

It has previously been the practice in paper mills to effect the partial separation of such im-

purities by causing the suspension to flow at reduced speeds into settling troughs provided with riffles, but the separation in these devices is far from complete. It has also sometimes been the practice to use centrifugal force to increase the inertial reaction and for this purpose the suspensions have been passed into rapidly rotating mechanical devices which of necessity are of complicated construction, expensive to erect and maintain in operation. The present invention on the other hand, while utilizing centrifugal force, does not require any moving mechanical parts other than a pump to impart pressure to the stream of the suspension being treated. According to this invention, certain vortices are established with a stream of the liquid being treated, in such manner that the desired liquid suspension may be withdrawn from the vortices while the undesired impurities are quite independently expelled from the vortices and so entrapped that they cannot return thereto, but are permitted to settle in a quiescent body of fluid apart from the vortices. While it has heretofore been proposed to remove relatively heavy particles, such as sand, from water supplies by the establishing of a vortex in the water, such problem has not involved the difficulty of retaining material such as paper pulp and China clay in the suspension, nor the problem of such complete removal of the particles of impurities as is required for uniformly 25 satisfactory paper stock. It has also been proposed to remove particles of heavy impurities, from paper pulp by establishing a vortex in a stream of the stock, but prior to this invention such attempts have been unsuccessful in removing the impurities to a degree such as to make 30 possible a perfected paper product unless supplemental apparatus is provided for removing the finer and lighter impurities.

While for the above reasons the invention is 40 particularly useful for paper pulp cleaning, important features of the invention are useful for treating various other forms of fluid suspensions for the purpose of classifying the suspended materials or removing undesired portions thereof. 45

Various further and more specific objects, features and advantages will more clearly appear from the detailed description given below, taken in connection with the accompanying drawing which form a part of this specification and illustrate merely by way of example certain preferred 50 forms of the apparatus of the invention.

The invention consists in such novel features, arrangements and combinations of parts as may be shown and described in connection with the ap- 55

paratus herein disclosed, and also such novel methods as are disclosed and described herein-after.

In the drawing Fig. 1 comprises a vertical sectional view of one unit of the apparatus embodying the invention and in which the method of the invention may be carried out;

Fig. 2 is an enlarged vertical sectional view of a portion of the apparatus of Fig. 1 and illustrating somewhat schematically the form of the vortices established within the device;

Fig. 3 is a plan view illustrating the manner of connecting a plurality of the units of the apparatus;

Fig. 4 is a vertical sectional view of a portion of the apparatus in a modified form; and

Fig. 5 is a vertical sectional view of an alternative embodiment of the apparatus.

The apparatus of Fig. 1 may include a head piece 10 comprising for example a casting provided with an inlet connection as at 11 in the form of a somewhat tapered nozzle discharging tangentially into an annular space 12 of somewhat spiral form and surrounding an outlet connection as at 13. The outlet connection may comprise a trumpet-shaped pipe located axially of the head piece with its lower and more restricted end as at 14 extending substantially below the inlet connection.

The main body of the device may comprise an upper cylindrical section or chamber as at 15 and a lower chamber as at 16 preferably similar to the upper chamber, although not necessarily so. An apertured disc as at 17 may be interposed transversely between the chambers 15 and 16. This disc is preferably formed of a pliable sheet of rubber or other flexible or suitable material. This disc may initially be flat, as indicated by the dotted lines, or if desired it may be made normally somewhat conical as shown in full lines. The conical form of the disc is shown somewhat exaggerated for clearness. When the disc is initially flat, it is preferably made of such flexible material as above indicated, but under the pressure conditions in the device as hereinafter described, it will assume the conical shape. The most suitable size of the central aperture 18 within the disc 17 may be determined by trial, but it is found that the diameter of the aperture is generally preferably made somewhat less than the diameter of the restricted outlet 14 and in the neighborhood of three-eighths of the diameter of the chamber 15.

While the disc 17 if desired may be made of relatively rigid hard metallic sheet material, it has been found that if the material being treated embodies much sand or grit, such a metallic disc will be rapidly worn away, whereas a rubber or yieldable disc or partition member will withstand the highly abrasive action of the sand for very long periods without noticeable wear. The use of a rubber or other pliable disc is also of an advantage in that it tends to automatically assume such a conical shape or sagging position under the pressures of the vortices hereinafter described, as will result in very effective action in permitting proper downward movement and separation of the impurities from the liquid within and around the zone of the disc, and causing the impurities to be entrapped below the disc and prevented from rising to the outlet 14.

At the lower end of the chamber 16 another transverse apertured disc or partition as at 19 may be provided, which also may be of rubber

or other pliable material as with the case of the disc 17, although not necessarily so. The disc 19 may be formed with a central aperture as at 20 of a size generally smaller than that of the aperture 18 in disc 17. The disc 19 is also preferably provided with one or more smaller apertures as at 21 located intermediate the walls of the chamber 16 and the axis thereof—preferably rather nearer the walls of the chamber.

A further small chamber 22 is provided beneath the disc 19 and preferably, although not necessarily, this chamber is in the form of an inverted cone as shown.

The various chamber portions of the device as above described may be secured together and to the head piece as by flanged connections as shown, the flanges being suitably bolted or otherwise secured together in any desired well-known manner.

The lower end of the conical chamber 22 may be connected through a normally open valve as at 23 to a waste pipe 24 including if desired a length of transparent tubing which forms a "sight glass" in which the waste material may be viewed as it settles through the clear quiescent liquid at this point. The lower end of the waste pipe 24 may be connected to a waste receiver or reservoir as at 25 which may be made of metal or may comprise a glass bottle. This chamber which is kept sealed during the normal operation of the equipment, is initially filled with clear liquid such as water, to provide a collecting chamber for the waste material which gradually displaces the water. The waste receiver or chamber 25 may be provided with an air discharge cock 26 and with a water pipe connection as at 27. If desired, the lower end of the receiver 25 may be provided with a valved outlet as at 28.

The operation of the device of Fig. 1 will be more readily apparent from the diagram of Fig. 2. The prepared pulp suspension or other fluid suspension to be treated may be conducted into the inlet 11 under a substantial pressure created by a suitable pump for example. Since the suspension is discharged from the inlet 11 tangentially into the annular space 12, it will be forced downwardly in a spiral path—i. e. more specifically a substantially helical path, forming an annular body of the suspension as at 30. It will be noted that the outer surface of the downwardly rotating body of the suspension 30 is substantially cylindrical all the way from the head piece nearly down to the disc or partition 17, and this body will occupy all of the space within the chamber 15 except for a central or core section occupied by an upwardly moving vortex 31 hereinafter described. The outer vortex or body of suspension 30 is so restricted and subject to pressure conditions such that the angular velocity therein about the central vertical axis of the device will be quite rapid, with the result that the centrifugal force causes the solid and heavier particles of impurities to be thrown outwardly toward the walls of the chamber 15. Since the vertical dimension of the body 30 is relatively great as compared with its diameter, for example at least in the neighborhood of from four to five times as great, this centrifugal action on the particles of impurities will be quite prolonged. This will insure that the heavier particles in all portions of the downwardly moving body of the fluid suspension will have opportunity to move close to the walls of the chamber, notwithstanding that from time to

time portions of pulp for example, may momentarily tend to obstruct this desired movement of the heavier particles. Then as the fluid in the vortex 30 approaches the disc 17, it will be forced inwardly toward the axis of the device, and at the same time the heavier particles will be drawn downwardly and along the inside surfaces of the chamber 15 and then radially inwardly along the upper surface of the disc 17 toward the central aperture 18. As the fluid thus comes into the neighborhood of the aperture 18, a small inner portion thereof (practically free of impurities) may be deflected upwardly into the central vortex 31, but the greater part of the fluid will be passed as an annular downwardly moving helix or vortex through the aperture 18. As a result of the restriction interposed by the aperture 18, the angular velocity of this downwardly moving helix will be greatly increased, thus insuring that substantially all of the particles of impurities therein, together with particles previously expelled to the outer surfaces of the helix, will be passed through the aperture 18 at the very periphery thereof. Once these particles have passed through the aperture 18, the disc 17 serves to entrap them against their returning up into the chamber 15. The orifice 18 is such as to offer only a momentary restriction to the flow, allowing the vortices to almost immediately expand again and adapt themselves to the contour of the chamber.

Below the aperture 18 the helical downwardly moving body or vortex will expand in diameter as indicated at 30' and continue in the form of another hollow substantially cylindrical body rotating downwardly to a point near the zone of the lower disc 19. The outer vortex within the chamber 16 will still retain sufficient centrifugal effect to maintain the particles of impurities near the walls of the chamber 16 as they settle or are carried toward the disc 19. When these particles arrive at the disc 19, a relatively gentle current of the liquid causes them to be carried through the outer aperture or apertures as at 21 in the disc 19 and into the conical chamber 22. However, most of the liquid of vortex 30' and particularly the inner portions thereof from which the particles of impurities have been largely removed, is deflected at the disc 19 centrally and upwardly to form an inner upwardly moving helix or vortex 31'.

The particles carried through the aperture or apertures 21 will settle to the bottom of the conical chamber 22 and the relatively small amount of fluid passing down through the apertures 21 will find a return passage upwardly through the central aperture 20. This fluid in passing up through aperture 20 may impinge upon the lower ends of the vortices 30' and 31' with an umbrella effect protecting the disc 19 against the abrasive action of any sand particles which might otherwise rapidly wear the disc at the areas of deflection of the downward vortex into the upward vortex.

In some cases if desired it may be found feasible to omit the disc 19, in which event the lower reversal of the vortices may occur within or near the conical chamber 22.

The upwardly rotating central core or vortex 31' being of a diameter and cross section somewhat less than the vortex 30', will have an increased angular velocity as compared with vortex 30'. Accordingly any of the impurities which are more difficult of removal or which may have

been swept upwardly in this central vortex, are now subjected to a further intense centrifugal action forcing such particles out of the central vortex and into the downwardly moving vortex 30'. This action may be made quite prolonged 5 and effective, inasmuch as the vortex 31' as shown is of a height many times greater than its diameter.

Yet despite the action of the device as thus far described, some of the particles of impurities more difficult of removal may be still retained in the central vortex 31'. However, the removal of these troublesome remaining particles may be insured by the restriction of the central vortex in its passage upwardly through 15 the middle of the aperture 18 as shown. That is, the restriction of the outer downwardly moving vortex at the aperture 18 in turn compels a restriction of the upwardly moving inner vortex with the result that the inner vortex within 20 the middle of the aperture 18 assumes a still higher angular velocity at that point. The particles of impurities remaining within the inner upwardly moving vortex at the aperture 18 need only travel radially outwardly a very short distance before they will be enveloped in the downwardly moving annular vortex at the outer edges of this aperture. This fact, together with the great angular velocity within the aperture, insures that the inner vortex as it emerges upwardly from the aperture 18, will be substantially wholly free of the undesired particles. And as this inner vortex continues on upwardly as indicated at 31, its angular and linear velocity will be sufficient (and greater than occurs in vortex 35 30), so as to prevent any of the undesired particles from being reintroduced into vortex 31.

Finally the treated suspension is withdrawn through the outlet 14 from within the upper end of the device. The lower end of the outlet 14 is 40 located sufficiently below the point of discharge of the incoming stream into the device so that the outer downwardly moving vortex will be firmly established before it passes the outlet 14. Thus the direct passage of any of the incoming 45 fluid into the outlet will be prevented. It will be further noted that the inner lower end of the outlet 14 is relatively restricted as compared with the cross section of the inlet, and so as to conform to or be no greater than the cross sectional 50 area of the upwardly flowing vortex 31. This further insures that none but the treated fluid will be allowed to escape through the outlet. At higher points the outlet conduit may be expanded in cross sectional area so as to not create any 55 excessive back pressure in the apparatus.

Liquid suspensions are preferably introduced into the device in such manner as to avoid introduction of any substantial amounts of air or gas therewith which might interfere with the 60 above described formation of the vortices. However, the centrifugal action of the vortices will ordinarily be so intense as to cause a small substantially evacuated space to be established along the entire vertical axis of the chambers 15 and 16 65 as indicated by the wavy central lines 32.

The impurities settling in the chamber 22 will further slowly settle through the normally open valve 23, "sight glass" 24 and into the receptacle 25, these parts being filled with a quiescent body 70 of liquid such as water introduced before the apparatus is placed in operation. As the receptacle 25 becomes filled with the impurities, they will serve to gradually displace the liquid and except for this very slow gradual upward 75

movement of the displaced liquid, the liquid below the conical chamber 22 will be free of motion. Thus the apparatus not only provides repeated and prolonged opportunity for the particles of impurities to be centrifugally removed from the vortices of the pulp suspension, but the apertured disc arrangements at 17 and 19 serve to entrap these particles against any possibility of their return toward the pulp outlet. And the portions below the disc 19 serve to maintain a quiescent body of liquid into which the particles of impurities may settle without possibility of their being again agitated and entrained in the vortices.

From time to time, for example once a day, as the receptacle 25 may become filled with impurities, the valve 23 may be closed for a moment while the receptacle 25 is emptied through its valved outlet 28 and then refilled with fresh water through the supply pipe 27. Then upon closing valve 28, the valve 23 may be opened again. During the short interval of cleaning the receptacle 25, the impurities being removed may accumulate in the conical chamber 22 without difficulty. Accordingly, the device may be maintained in continuous operation during the cleaning of the receptacle 25.

If desired, the walls of the chambers 15 and 16 may be made of transparent material so that the action of the vortices may be readily observed, but this is unnecessary once a typical unit has been placed in proper operation for a particular purpose.

In controlling the vortices in the manner above described, the dimensions of the various parts may become of substantial importance. In the particular example shown in Fig. 1 as used in purifying paper pulp stock, pumped into the apparatus at 25 pounds of pressure, for example, the preferred dimensions are as follows:—The length of the cylinder comprising chambers 15 and 16, is about 42 inches and has a diameter of 4 inches. The inlet pipe 11 has a diameter of 3 inches, and the restricted lower end of the outlet pipe 14, a diameter of 2 inches. The aperture in the disc 17 has a diameter of 1½ inches. The central aperture in the disc 19 has a diameter of 7/8 inch, and the aperture 21 a diameter of 5/8 inch, although the latter may be varied depending on whether one or more of such apertures 21 are provided. The height of the conical chamber 22 is 6 inches and may be provided with an outlet pipe 1 inch in diameter, although the dimensions and shape of the chamber 22 and of the waste outlet therefrom are not of such importance as other factors above mentioned.

A single unit as above described has a capacity of about 150 imperial gallons of liquid per minute. Assuming a stock consistency of about 0.5%, each of these units can be used to treat in the neighborhood of 5 to 6 tons of paper stock (dry basis) per day, if supplied with stock at a pressure of about 25 pounds per square inch. With this supply pressure, the pressure difference between the inlet and outlet may be maintained at about 15 pounds per square inch, or more. With the particular device as above specified, it has been found important to maintain a pressure drop therein, at least as great as 15 pounds per square inch, and the inlet and outlet pressures are of less importance so long as such pressure drop is maintained. It is of substantial importance that the diameter of the chambers 15 and 16 be maintained small in comparison with the height. Most effective results may be obtained

when the total height of the chambers 15 and 16 is in the neighborhood of ten times their diameter. If the diameter is increased, the efficiency of separation of the impurities will be greatly diminished, assuming pressure conditions are kept within practical limits.

With the various dimensions as above specified, the greatest cross sectional area of the downwardly and helically flowing annular body of the suspension will be in general about the same as the cross sectional area of the stream introduced through the inlet 11. That is, there will be no material enlargement of the cross sectional area of the annular space through which this stream must pass in forming the prolonged downwardly flowing annular body. This relationship appears to be of very substantial importance in securing the most effective separating action in the device. Such relationship insures that the fluid in the downwardly flowing vortex will have sufficient force at all points to rather sharply distinguish this vortex from the inner upwardly moving core of fluid, thereby preventing intermingling of the treated and untreated fluid, despite the prolonged extent of both vortices. Furthermore, a downward vortex of a cross sectional area about the same as that of the incoming stream, insures that the inner, upward vortex will be properly confined by the outer vortex so that the inner vortex will be of smaller cross section and hence have a higher angular velocity, assisting in the final effective removal of the particles and preventing redeflection of removed particles into the inner core before it is withdrawn. This relationship of the cross sectional areas of the vortices further makes it possible to use an outlet conduit of such size as to be filled by the upwardly flowing inner core to the exclusion of adjacent downwardly flowing untreated liquid, while the outlet conduit may still be of a diameter sufficient to avoid undue back pressures in the device.

The interior surfaces of the chambers 15 and 16 should be made quite smooth so as to prevent the formation of irregular eddy currents interfering with the action of the vortices, as above described. The extended cylindrical form of these chambers greatly contributes to the substantial uniform maintenance of the rather sharply defined and extended concentric downwardly and upwardly moving vortices, once the vortices have been normally established.

With the device used as above disclosed, it has been determined that under actual operating conditions in paper mills over a considerable period, at least 94% of the total impurities (oversize particles and particles heavier than the pulp fiber) may be removed from the liquid suspension, and the particles thus removed constitute substantially all of those which would otherwise cause noticeable imperfections in the paper. The pulp stock treated with this device and without further treatment, has been found to be more free of the troublesome impurities than is the case with pulp stock heretofore treated with other devices even including very expensive centrifugal equipment with mechanically rotating parts.

Fig. 3 illustrates the manner in which several of the above described units of the device may be interconnected with a single pump for treating a greater volume of liquid. In Fig. 3 a common feed manifold is indicated at 40 to which inlet pipes as at 11' are connected. A common outlet manifold for the treated liquid is indicated at 41, connected to the outlets 13 of the several units. The manifold 40 is shown as connected

to a suitable pump as at 42 for supplying the necessary pressure to the incoming liquid.

Fig. 4 illustrates an alternative construction which may be used in lieu of the conical chamber 22 above described. That is, in Fig. 4 a lower or conical chamber 43 may have its inner surfaces formed with a plurality of vertically and inwardly extending fins as at 44, for diminishing the turbulence within this chamber and thereby affording greater opportunity for the particles of impurities to promptly settle, and preventing any abrasive action of such particles tending to wear away the walls of the chamber. This form of conical chamber is particularly useful in the event the disc 19 is omitted.

In Fig. 5 an alternative embodiment of the apparatus is shown which may be similar to that of Fig. 1 except for the features hereinafter described. The main body of the device of Fig. 5 may comprise a single and vertically elongated cylindrical chamber 35 corresponding in general as to function to the chamber 15 above described, although of sufficient length to accomplish in part the functions of chamber 16 also. An apertured disc 36 corresponds in general to the disc 17 above described. And the action of the vortices 37 and 38 as restricted in passing through the disc 36, will be similar to the action of the vortices within the aperture of the disc 17 above described. The functions of the chambers 16 and 22 explained in connection with Fig. 1, are in Fig. 5 combined to some extent within a single conical chamber 39, although of course the vortices within this chamber will be greatly restricted in length as compared with those occurring in chamber 16. With the disc or partition 36 arranged as in Fig. 5, to provide a single passage of the fluid through a confining aperture and trap for the impurities or heavier particles, this construction has been found to operate successfully and efficiently in normal commercial use.

It will be apparent that this invention provides a simple form of construction adapted for a wide variety of uses in classifying materials conducted in a stream of fluid. And the construction has no moving parts or other parts subject to any appreciable wear. No great expense for power is required in operating the device. The space required for an installation is small and the units when used for paper pulp cleaning may be located close to the paper machines using generally the existing pipe lines, valves, etc., and frequently the same pump previously used for supplying the pulp stock to the machines.

While the invention has been described with respect to certain particular preferred examples which give satisfactory results, it will be understood by those skilled in the art, after understanding the invention, that various changes and modifications may be made without departing from the spirit and scope of the invention, and it is intended, therefore, in the appended claims to cover all such changes and modifications.

65 What is claimed as new and desired to be secured by Letters Patent is:

1. In apparatus for separating relatively heavy particles from fluid, a disc of rubber or the like flexible material supported at its periphery and having a central aperture, a chamber above said disc, means for establishing a downwardly and helically flowing annular body of the fluid in said chamber impinging against said disc around said aperture and deflecting the areas 70 of the disc substantially downwardly with said

helically flowing body extending in restricted form through said aperture, means including an enclosed chamber below said disc for causing said fluid to return from below said disc upwardly through the center of said aperture while still flowing in a helical path, and an enclosed quiescent body of fluid below said last named chamber and normally in communication therewith for receiving said particles.

2. Apparatus for separating relatively heavy particles from fluid, comprising an upstanding cylinder of a height at least several times its diameter, a partition with a central aperture and extending transversely across the lower end of said cylinder, a chamber below said partition, a closure for the top of said cylinder, means for introducing tangentially at said top a stream of the fluid under sufficient pressure for establishing a downward helically flowing annular body of fluid filling the peripheral zones of the cylinder and extending in restricted form through said aperture and thence in expanded form into said chamber, the cross sectional area of said introduced stream approximating that of said helically flowing body in the cylinder, and an outlet conduit with a restricted mouth positioned in the space within the upper end of said cylinder, and extending upwardly, the parts being of such proportions and shape that the fluid after entering said chamber returns upwardly within said annular body, forming a helical core of high angular velocity, confined within and by said downwardly flowing body and filling said outlet to the exclusion of adjacent downwardly flowing fluid.

3. Apparatus for separating relatively heavy particles from fluid, comprising an upstanding substantially cylindrical chamber, a closure for the top thereof, means for forcing a stream of the fluid of such dimensions and pressure into the upper end of said chamber as to establish a downwardly flowing outer vortex occupying the peripheral zones thereof, the fluid of said vortex returning as an upwardly flowing inner vortex confined within and by the downward vortex, an outlet for withdrawing the fluid of said upward vortex upwardly from within the upper end of said outer vortex, a partition extending across said chamber at a point spaced substantially from both the upper and lower ends of said chamber, said partition having a central aperture whereby said vortices are greatly restricted in passing concentrically therethrough, a second partition extending across said chamber in the neighborhood of the lower end thereof and being apertured to permit a relatively gentle current of fluid to carry particles from said downward vortex to a point below said second partition, and permitting such current to return to the upward vortex, and means normally enclosing the space below said second partition against other escape of fluid therefrom.

4. Apparatus for separating relatively heavy particles from fluid, comprising an upstanding substantially cylindrical chamber, a closure for the top thereof, means for forcing a stream of the fluid of such dimensions and pressure into the upper end of said chamber as to establish a downwardly flowing outer vortex occupying the peripheral zones thereof, the fluid of said vortex returning as an upwardly flowing inner vortex confined within and by the downward vortex, an outlet for withdrawing the fluid of said upward vortex upwardly from within the upper end of said outer vortex, a partition extending across

- 5 said chamber at a point spaced substantially from both the upper and lower ends of said cylindrical chamber, said partition having a central aperture whereby said vortices are greatly restricted in passing concentrically therethrough, an enclosed quiescent body of fluid below the lower ends of said vortices, and means normally providing a restricted communication between such body and said lower ends.
- 10 5. In apparatus for separating relatively heavy particles from paper pulp water suspensions, a disc supported at its periphery and having a central aperture, a chamber above said disc means including an inlet at the top of said chamber for establishing a downwardly and helically flowing annular body of the water suspension in said chamber impinging against said disc with said helically flowing body extending in restricted form through said aperture and expanding again below said aperture, means including an enclosed chamber below said disc for then causing such water suspension to return upwardly through the center of said aperture while still flowing helically, a discharge conduit for said suspension, 20 said conduit having its mouth within the upper portion of said first named chamber but below said inlet and within said annular body for withdrawing from the apparatus such upward helical flow exclusively of the adjacent downward flow, 25 and an enclosed quiescent body of water beneath and spaced from said helical flows for receiving said particles.
6. The method of separating relatively heavy particles from fluid, which comprises establishing a downwardly flowing vortex of the fluid confined under substantial pressure and in the shape of a vertically extending substantially cylindrical body of a height at least several times greater than its diameter, deflecting the fluid at the lower 40 end of said vortex upwardly and centrally of said vortex whereby a second and upwardly flowing vortex is formed within and confined by said first named vortex, said second vortex also being of a vertically extended substantially cylindrical shape 45 and having a higher angular velocity than the first, withdrawing the fluid comprised in the second vortex, axially and upwardly from within the upper end of the first vortex, without directly withdrawing any substantial amount of the fluid 50 of the first vortex, and greatly restricting the diameter of said first vortex and thereby causing restriction of the second vortex therein at a point spaced substantially below the upper ends 55 of the vortices whereby the angular velocities of the vortices are increased at such restriction, and providing a quiescent fluid body beneath and normally communicating with the zone of said deflecting, whereby said heavy particles in the upward vortex are thrown by centrifugal force 60 into the downward vortex, and with increased effectiveness at said restriction, and such particles in the downward vortex are thrown to the periphery thereof and carried down to said quiescent body.
- 65 7. The method of separating relatively heavy particles from liquid suspensions of fibrous lighter material, which comprises so introducing a stream of said suspension into a chamber as to establish a downwardly flowing vortex of the liquid suspension confined in said chamber under substantial pressure and in the shape of a vertically extended substantially cylindrical body of a height at least 70 several times greater than its diameter, deflecting the liquid suspension at the lower end of said vortex upwardly and centrally of said vortex

whereby a second and upwardly flowing vortex is formed within and confined by said first named vortex, said second vortex also being of a vertically extended substantially cylindrical shape and having a higher angular velocity than the first, withdrawing the desired liquid suspension comprised in the second vortex, axially and upwardly from within the upper end of the first vortex, without directly withdrawing any substantial amount of the liquid of the first vortex, the stream of the suspension as withdrawn being substantially restricted as compared with the cross section of the introduced stream, and providing a normally enclosed quiescent body of liquid beneath the zone where said deflecting occurs and in restricted communication with such zone, whereby said heavy particles in the upward vortex are thrown by centrifugal force into the downward vortex and such particles in the latter vortex are thrown to the periphery thereof and carried down to said quiescent liquid.

8. The method of separating relatively heavy particles from liquid suspensions of lighter or finer material, which comprises establishing a downwardly flowing vortex of the liquid confined under substantial pressure and in the shape of a vertically extended substantially cylindrical body of a height at least several times greater than its diameter, deflecting the liquid at the lower end of said vortex upwardly and centrally of said vortex whereby a second and upwardly flowing vortex is formed within and confined by said first named vortex, said second vortex also being of a vertically extended substantially cylindrical shape and having a higher angular velocity than the first, withdrawing the desired liquid suspension comprised in the second vortex, axially and upwardly from within the upper end of the first vortex, without directly withdrawing any substantial amount of the liquid of the first vortex, and greatly restricting the diameter of said first vortex and thereby causing restriction of the second vortex therein at a point intermediate the upper and lower ends of the vortices whereby the angular velocities of the vortices are increased at such restriction, and providing a quiescent body of liquid beneath the zone of said deflecting, and with restricted communication with said zone, whereby said heavy particles are thrown by centrifugal force to the periphery of the downward vortex and are carried down to said quiescent liquid.

9. The method of separating relatively heavy or solid particles of an abrasive character from fluid, which comprises establishing a downwardly and helically flowing annular body of the fluid, providing an annular obstruction having a passage therethrough surrounded with downwardly yielding areas, said obstructions being in the path of such flow for directing the same as a more restricted helically flowing annular body through such passage, then returning said fluid while still flowing helically, upwardly, axially of and within said annular body of fluid to a point of withdrawal, whereby said particles are thrown by centrifugal force to, and carried down in the peripheral zones in the downwardly flowing fluid and prevented by the action of said obstruction from rising to said point of withdrawal.

10. The method of separating relatively heavy particles from liquid fibrous pulp suspensions, which comprises tangentially introducing a stream of the liquid suspension under substantial pressure into a space so restricted as to establish a downward helically flowing annular body of

the liquid suspension extending substantially cylindrically for a distance many times its diameter and of a cross sectional area not materially greater than said stream, then causing such 5 helically flowing liquid suspension to be deflected inwardly of itself and upwardly forming a substantially distinct core of higher angular and linear velocity within and confined by said annular body, withdrawing the liquid suspension of 10 such core only, upwardly from within the upper end of said annular body, and providing an enclosed quiescent body of liquid below the lower end of said annular body for receiving said particles.

15 11. The method of separating relatively heavy particles from liquid, which comprises establishing a downwardly and helically flowing annular body of the liquid, providing an annular obstruction in the path of such flow for directing 20 the same as a more restricted helically flowing annular body through the center of such obstruction, then causing such helical flow to expand and continue downwardly beneath the obstruction, then returning said liquid while still flowing 25 helically, upwardly, axially of and within said annular body of liquid to a point of withdrawal, whereby said particles are thrown by centrifugal force to, and carried down in the peripheral zones in the downwardly flowing liquid 30 and prevented by the action of said obstruction from rising to said point of withdrawal, and maintaining a distinct substantially quiescent body of liquid below the zones of such helical flows for receiving said particles.

35 12. Apparatus for separating solids from fluid suspensions comprising a closed vertical stationary chamber having a cylindrical portion long in relation to its diameter, means for admitting the fluid suspension tangentially under pressure to the chamber adjacent the top of the cylindrical portion, a disc extending transversely across the space within said cylindrical portion and having therein a central opening axially disposed of said chamber, means for discharging fluid upwardly 40 from a point axially located adjacent the top but below the inlet to said chamber, a lower discharge outlet for said solids located substantially axially of the chamber below said disc, and a chamber having its side walls extending downwardly to 45 said outlet from points on said disc spaced from said opening.

50 13. Apparatus for purifying fluid paper-making stock and the like which comprises a plurality of units as defined in claim 12 in combination 55 with a common feed manifold for all said units and a pump for exerting a constant pressure on stock flowing through said manifold to said units.

55 14. Apparatus for purifying paper stock comprising a closed and stationary cylinder long in relation to its diameter, a tangential inlet adjacent the top, a top discharge outlet pipe projecting into the cylinder to a point below said inlet, a substantially plane disc having an opening 60 therein, said disc extending transversely across the space within the lower portion of said cylinder, and a chamber of inverted conical shape below said disc at the base of said cylinder with a bottom discharge outlet therein, the side walls 65 of said chamber extending down from points in the plane of said disc spaced from said opening, said top and bottom outlets and said opening being arranged axially of said cylinder.

15. Apparatus for purifying fibrous pulp stock comprising a closed cylinder long in relation to its diameter and subdivided into three superposed separating chambers, a disc with a central opening therein constituting the lower wall of each 5 of the two uppermost chambers, said discs extending over the greater part of their areas in a general direction at right angles to the axis of said cylinder, a discharge opening at the base of the other of said chambers, a tangential inlet 10 adjacent the top of said cylinder and an axially disposed outlet pipe also adjacent the top of said cylinder and extending below said inlet, the two upper chambers constituting at least the major portion of the cylinder and the third the base 15 thereof.

16. Classifying apparatus of the character described comprising a closed chamber having therein at least two superposed unobstructed cylindrical portions, long in relation to their 20 diameter, and a base portion all with a common vertical axis, a disc with a central opening therein constituting the lower wall of each of said cylindrical portions, a discharge opening in said base portion at a point removed from the lower 25 of said discs, the cylindrical portions constituting at least the major part of said chamber, another discharge opening extending axially and upwardly from within the upper cylindrical portion, and an inlet extending substantially tangentially into the space surrounding said last 30 named discharge opening.

17. Apparatus of the character described comprising a closed chamber having therein two superposed unobstructed, cylindrical, axially disposed portions, long in relation to their diameter, a disc with a central opening therein at the base of each portion and anchored in the walls thereof, a settling portion below the lower disc with a discharge outlet at a point removed from said lower disc, another discharge opening extending axially and upwardly from within the upper cylindrical portion, and an inlet extending substantially tangentially into the space surrounding said last named discharge opening. 40

18. Apparatus for separating relatively heavy particles from a fluid, comprising an upstanding cylinder of a height at least several times its diameter, a partition with a central aperture and extending transversely across said cylinder, at a substantial distance from its upper end, a chamber below said partition, a closure for the top of said cylinder, inlet means for introducing tangentially at said top a stream of the fluid of such dimensions and pressure as to establish a downward helically flowing annular body of the fluid occupying the peripheral zones of the cylinder and extending in restricted form through said aperture and thence into said chamber, an outlet conduit having its mouth positioned in the space 60 within the upper end of said cylinder but below said inlet means, said conduit extending upwardly, the parts being of such proportions and shape that the fluid after entering said chamber returns upwardly within said annular body, forming a 65 helical core of high angular velocity, confined within and by said downwardly flowing body and filling said outlet to the exclusion of adjacent downwardly flowing fluid, and a receptacle containing a quiescent body of fluid, normally communicating with the bottom of said chamber for receiving said particles. 70

HORACE FREEMAN.

CERTIFICATE OF CORRECTION.

Patent No. 2,102,525.

December 14, 1937.

HORACE FREEMAN.

It is hereby certified that error appears in the printed specification of the above numbered patent requiring correction as follows: Page 1, second column, line 50, for the word "form" read forms; line 50-51, for "illustrate" read illustrates; page 5, first column, line 74, claim 1, strike out the words "around said aperture" and insert the same after "disc", line 75, same claim: and that the said Letters Patent should be read with these corrections therein that the same may conform to the record of the case in the Patent Office.

Signed and sealed this 1st day of March, A. D. 1938.

(Seal)

Henry Van Arsdale,
Acting Commissioner of Patents.
